ELECTROLYTIC CONDENSER

Filed May 17, 1924

INVENTOR

Harry R. Van Deventer

UNITED STATES PATENT OFFICE

HARRY R. VAN DEVENTER, OF NEW YORK, N. Y., ASSIGNOR TO DUBILIER CONDENSER CORPORATION, OF NEW YORK, N. Y., A CORPORATION OF DELAWARE

ELECTROLYTIC CONDENSER

Application filed May 17, 1924. Serial No. 714,139.

I have invented improvements in electrical condensers; especially electrolytic condensers, the electrodes of which are of conductive material immersed in a liquid having the necessary properties.

An object of this invention is to provide an electrolytic condenser that is quite simple in design and can be built for general use, and of such construction that heating in operation can be prevented. Preferably the electrodes are hollow so that a cooling agent can be circulated through them, and the temperature of the condenser thus easily controlled.

Other objects and advantages of this invention will be apparent from the following description and the novel features thereof are precisely defined in the appended claims. But the disclosure is of course illustrative only and I reserve the right to make changes in structural details without departing from the principle which governs the invention.

On the drawing

The figure is a view partly in section showing a condenser in which the characteristics of my invention are embodied.

Briefly stated, I employ in practice two or more coils of pipe, of different polarity, in a suitable electrolyte. The pipes are electrically insulated from one another, and connected to the opposite terminals of an electric circuit. Through the pipes a cooling medium, such as oil or some other agent, is forced by suitable pumping mechanism.

The coils of pipe are shown at 1, 2, 3 and 4. Coils 1 and 3, for example, are of one polarity and coils 2 and 4 of the opposite polarity. All the coils are concentric and each comprises several turns or layers, one above the other, in a tank or container 5 holding the electrolyte 6. This electrolyte is deep enough to submerge all the coils, and the tank may be provided with a suitable refractory or chemically inert lining 7 to resist the action of the electrolytic liquid and thus prevent corrosion. Each of the coils 1, 2, 3 and 4, which are of course of an electrically conductive substance, such as metal, may have an insulating coating 8 on its outside over the entire surface with which the

electrolyte 6 makes contact. I may shape the tank 5 to give it an outturned rim or flange 9 at the top, perforated at several points 10, upon this rim may be placed a closure 11, secured by fastening devices, such as screws or rivets, passing through the perforations or apertures 10. This cover should be held as tight as possible to prevent evaporation of the electrolyte 6, but can be removed to renew or replenish the liquid.

The two coils 1 and 3 are joined together at their upper ends by a section of pipe 13. They are wound downward towards the bottom of the tank 5, and their lower ends are united by vertical pieces of piping 14 to a common outlet pipe 15. The ends of the pipes 13 and 15 are secured to the inner ends of sleeves or couplings 16, of insulation, made fast in openings in the side of the tank near the top. The outer ends of the sleeves 16 are joined by pipes or conduits 17 and 18 leading to the opposite ends of a coil 19 in a cooling tank 20. In the line of the pipe 17 may be a pump 21 to maintain a circulation of a cooling liquid through the coils 1, 3 and 19, and the tank 20 may have an inlet pipe 22 and an outlet pipe 23 so that there may be a continuous flow of water through the tank 20 over the coil 19. Thus, when the cooling agent from the coils 1 and 3 in the tank 5 reaches the coil 19, all the heat removed by this agent from the coils 1 and 3 will be carried away by the water flowing over the coil 19 and through the tank 20.

A pipe 24 unites the tops of the other two coils 2 and 4 in the tank 5. These two coils are also wound downward and pipes 25 join their lower ends to a common outlet pipe 26. The pipes 24 and 26 are also affixed at their ends into insulating couplings 16, similar to the couplings already mentioned in the side of the tank 5 near the top; and the pipe 24 may be connected to the pipe 17. If desired a double coupling 28 may be employed to unite to the pipe 17 the two sleeves 16 receiving the ends of the pipes 13 and 24, and a pipe 27 may be used to connect the coupling 16 receiving the pipe 26, to the same end of the coil 19 as the pipe 18. As shown the two pipes 18 and 27 may be united to the coil 19.

by a single coupling similar to the coupling 28.

The coils 1 and 3 thus constitute hollow electrodes, and so do the coils 2 and 4; the coil 3 being between the coils 2 and 4; so that the electrodes are in alternation. To the pipe 13 may be connected the terminal 29 of an electric circuit; and the opposite terminal 30 of the circuit may be joined to the pipe 24. Then 10 the coils 1 and 3, 2 and 4, are of opposite polarity. The two sets of coils are insulated from each other and the tank 5 by their coatings 8 and the insulating couplings 16, and in operation the circulating member 21 with 15 the cooling apparatus comprising the tank 20 and coil 19 constitute means capable of maintaining an ample flow of cooling agent through all of the electrode coils 1, 2, 3, and 4 to keep the temperature of the condenser 20 within the desired limits.

In practice binding posts may be mounted in any convenient fashion on the tank with leads to the coils 1 and 3, 2 and 4, inside.

Coils 1 and 3 are in multiple with each 25 other and so are coils 2 and 4, while the two groups or sets of electrode coils 1 and 3, 2 and 4, are connected in series with each other.

Having described my invention, what I believe to be new and desire to secure and protect by Letters Patent of the United States 30 is:—

1. A condenser comprising a container for a fluid, a coil of pipe comprising a number of turns each spaced axially from the others in said container and constituting an electrode, a second coil of pipe comprising a number of turns each spaced axially from the others and concentric with the first coil, the second coil constituting another electrode, said electrode being of opposite polarity, and means for circulating a cooling agent 35 through the pipes.

2. A condenser comprising a container for a fluid, a pair of coils of pipe therein, said 45 coils being concentric, and each consisting of a number of turns each spaced axially from the others, and connected in multiple, a second pair of coils in said container, each pair consisting of a number of turns one 50 spaced axially from the other, the second pair of coils also being connected in multiple, the coils being arranged in alternation, so that one coil of each pair will lie between the two coils of the other pair, and means for circulating a cooling agent through the coils.

3. A condenser comprising a container for a fluid, a coil of pipe comprising a number of turns each spaced axially from the others in said pipe, and constituting an electrode, a second coil of pipe comprising a number of turns each spaced axially from the others and concentric with the first coil, the second coil constituting another electrode, said electrodes being of opposite polarity, and means 60 for circulating a cooling agent through the

pipes, said coils each consisting of electrical-conductive material, having an exterior non-conductive coating.

4. A condenser comprising a container for a fluid, a pair of coils of pipe therein, said 70 coils being concentric, an each consisting of a number of turns each spaced axially from the others, and connected in multiple, second pair of coils in said container, each pair consisting of a number of turns each spaced axially from the others, the second pair of coils also being connected in multiple, the coils being arranged in alternation, so that one coil of each pair will lie between the two coils of the other pair, and means for 75 circulating a cooling agent through the coils, said coils each consisting of electrically conductive material, having an exterior non-conductive coating.

5. An electrical condenser comprising a 80 container for a fluid, a pair of coils therein which are concentric with each other and are joined in multiple, each coil consisting of a number of layers each spaced axially from the others, a second pair of coils joined 85 in multiple and each consisting of a number of layers each spaced axially from the others, the coils being arranged in alternation, so that one coil of each pair will be between the coils of the other pair, the two pairs of coils being of opposite polarity and consisting 90 of electrically conductive material, with an outside non-conductive coating thereon, cooling means outside of the tank, the coils having one end connected to one end of the 95 cooling means, and having their opposite ends also united to the other end of said cooling means, and a member associated with said cooling means for maintaining the circulation 100 of a cooling agent through said means and said coils.

6. A condenser comprising a container for a fluid, a pair of concentric coils in said 105 container, each coil consisting of a number of layers each spaced axially from the others, a second pair of coils in said container, each consisting of a number of layers each spaced axially from the others, the coils being in alternation so that one coil of each pair lies 110 between the coils of the other pair, said coils being of conductive material, with an outside non-conductive coating thereon, the coils of each pair being connected in multiple, cooling and circulating means for maintaining 115 the flow of a cooling agent through said coils, insulating bushings through which the coils can be placed in communication at one extremity with said cooling and circulating means, and insulating bushings through 120 which the opposite end of the coils can be placed in communication with cooling and circulating means, said bushings being mounted in said container.

7. An electrolytic condenser comprising a 125 container for a liquid, a pair of electrodes im-

mersed in said liquid, said electrodes being of opposite polarity and hollow so that a cooling agent can be passed through the same, pipes outside said container to pass the cooling agent therethrough, and insulating bushings mounted in a wall of the container to which said electrodes are connected, and held in fixed position by said container, said insulating bushings also serving to insulate the ends of the hollow electrodes from the ends of said pipes.

5 8. An electrolytic condenser as specified in claim 7 in which said bushings aid in supporting said hollow electrodes.

10 15 In testimony whereof I affix my signature.
